UNITED STATES PATENT OFFICE.

LOU B. KAUFFMAN, OF NEW YORK, N. Y., ASSIGNOR TO NATHAN STRAUSS & SONS, INC., OF NEW YORK, N. Y., A CORPORATION OF NEW YORK.

DESIGN FOR A PLATE OR SIMILAR ARTICLE.

Application filed March 26, 1927. Serial No. 21,353. Term of patent 14 years.

To all whom it may concern:

Be it known that I, LOU B. KAUFFMAN, a citizen of the United States, residing at Hotel Dauphin, Broadway and 67th Street, borough of Manhattan, city, county, and State of New York, have invented a new, original, and ornamental Design for a Plate or Similar Article, of which the following is a specification, reference being had to the accompanying drawing, forming part thereof.

The figure is a plan view of a plate or similar article showing my new design. The design comprises a unitary design which is repeated, and therefore only a segment of the complete design will be shown including the unitary design; it being understood that this is repeated around the border of the article shown.

I claim:

The ornamental design for a plate or similar article substantially as shown and described.

LOU B. KAUFFMAN.

CERTIFICATE OF CORRECTION.

esign Patent No. 73,086.

Granted July 19, 1927, to

LOU B. KAUFFMAN.

It is hereby certified that the name of the assignee in the above numbered patent was erroneously written and printed as "Nathan Strauss & Sons, Inc.", whereas said name should have been written and printed as "Nathan Straus & Sons, Inc.", as shown by the records of assignments in this office; and that the said Letters Patent should be read with this correction therein that the name may conform to the record of the case in the Patent Office.

Signed and sealed this 4th day of October, A. D. 1927.

Seal.
